UNITED STATES PATENT OFFICE

RICHARD M. CRAIG, OF SAN ANTONIO, TEXAS, ASSIGNOR, BY MESNE ASSIGNMENTS,
TO THOMAS W. MENEFEET, OF SAN ANTONIO, TEXAS

DISPLAY APPARATUS

Original application filed December 29, 1925, Serial No. 78,244, now Patent No. 1,698,219, dated January 8, 1929. Divided and this application filed January 7, 1929. Serial No. 330,935.

This invention relates to display apparatus and more particularly to an advertising sign of the type disclosed in my copending application, Serial No. 78,244, filed December 29, 5 1925, now Patent No. 1,698,219, issued January 8, 1929, and of which the present application is a division.

One object of the invention is to provide a sign having advertising matter painted thereon in pigment colors and so arranged that when subjected to spectral rays of appropriate colors alternately turned on and off, portions of the advertising matter will be alternately displayed and absorbed while 15 other portions will be continuously displayed.

Another object of the invention is to provide a sign which will be attractive in appearance and hold the interest of a person 20 observing the same by the novel manner in which the subject matter is displayed upon the sign board.

In the accompanying drawing:

Figure 1 is a schematic view illustrating 25 one application of the principles of the present invention, wherein one kind of background is utilized in combination with matter represented thereon in neutral color and other matter in a single primary pigment 30 color;

Figure 2 is a similar view illustrating another application of the principles of the 35 invention, wherein the matter to be displayed is represented upon a background of a different character than that shown in Figure 1, and

Figure 3 is a schematic view illustrating another application of the principles of the invention, wherein the entire display surface 40 may be flooded with white light for a period of time and during another period of time may be displayed in light rays of contrasting colors.

In the description which is to follow reference will be made to pigment colors, and by 45 this term are meant colored pigments or the colors in which the images are represented on the display surface. Reference will also be made to spectral colors and by this is 50 meant the colors of the spectrum as repre-

sented by the colored light rays. Reference will likewise be made to neutral colors, and by neutral colors is meant colors which do not materially change under spectral color illumination or, in other words, those colors which display no decided color characteristics such as relate to primary colors.

Figure 1 of the drawing illustrates one application of the principles of the present invention. The numeral 1 indicates in general 60 the display surface, which may be a sign board or any other surface upon which advertising or other matter is to be represented. In this embodiment of the invention, the display surface is painted white or some other 65 light neutral color to provide a neutral background 2, and upon the mid-portion of the surface there is represented, in some dark neutral color or colors, an image 3 of the article to be advertised, it being understood, of course, that the representation is not limited to an article of merchandise but that any 70 matter may be represented on this portion of the background if such matter is intended to be continuously displayed to view, and it is 75 for this reason, as will presently be made apparent, that the matter is represented in a dark neutral color. In the particular illustration given, the representation 3 is that of a spark plug, and advertising matter relating 80 to the particular article is represented upon the background at opposite sides of the representation 3. Thus, as an illustration, the word "Spark", indicated by the numeral 4, 85 may be painted in red pigment upon the background at the left hand side of the representation 3, and the word "Plug", indicated by the numeral 5', may be painted likewise in red pigment, upon the background at the right hand side of the representation. This 90 constitutes, of course, merely a simple example of the application or the principles of the invention and the matters to be displayed may be of a more complex nature, depending upon the character of the display as a whole. There 95 are numerous light neutral colors and numerous dark neutral colors, and as an example of the use of such colors, the background 2 may be white, white lead, zinc white, or the like, and the representation 3 may be in brown, In-

dian red, black or the like. The invention contemplates successive illumination of the display surface by light rays of complementary colors such, for example, as red and blue, 5 and while any source of illumination may be employed, it is preferable to arrange, in proximity to the surface and in position to illuminate the same, a plurality of red electric light bulbs 5, and blue bulbs 6, the arrangement of 10 the bulbs being such that they will be symmetrically distributed as, for example, in the manner illustrated in Figure 1. In this embodiment of the invention, it is contemplated that the two lateral halves of the display 15 surface be successively illuminated by the complementary colors and, therefore, a suitable flashing mechanism is provided which is illustrated diagrammatically in Figure 1, and indicated in general by the numeral 7. 20 As a suitable example of such a mechanism or device, the same may comprise a disc 8 of insulating material in which are embedded a number of contact strips 9 of arcuate form and other contact strips 10 likewise of arcuate 25 form, the strips being positioned concentric to the axis of rotation of the disc 8 and said strips 9 and 10 being arranged in staggered relation. The numeral 11 indicates the source of current supply and the numeral 12 a conductor wire leading therefrom to, for example, the shaft 13 upon which the disc 8 is mounted, branch wires 14 extending from the shaft to the several contact strips 9 and 10. Brushes 15 and 16 are suitably mounted 30 in juxtaposition to the disc to respectively contact the strips 9 and 10 in the rotation of the disc 8, and another conductor wire 16' is led from the other terminal of the source of current supply and connected to one terminal of each of the sockets for the light bulbs 5 and 6. A conductor wire 17 is connected to the brush 15 and it, and branches leading therefrom, are connected to the other terminals of the sockets for the red light bulbs 5 at 35 the left of the display surface 1 and to the other terminals of the sockets for the blue light bulbs 6 at the right of said display surface, as shown diagrammatically in Figure 1 of the drawing. A conductor wire 18 and 40 branches therefrom are connected to the other terminals of the sockets for the blue light bulbs 6 at the left side of the display surface and to the other terminals of the sockets for the red light bulbs 5 at the right hand side of 45 the display surface. The arrangement of the contact strips 9 and 10 is such that, for example, when the receding end of one of the contact strips 9 passes beneath the brush 15, in the rotation of the flasher disc 8, the advancing end of the next adjacent contact strip 10 will ride into electrical contact with the brush 16. Due to the arrangement of the light bulbs and the manner in which they are 50 wired in connection with the flasher device, 55 of whatever character it may be, the red light

bulbs 5 at the left hand side of the display surface and the blue light bulbs 6 at the right hand side of the display surface will be simultaneously illuminated for a period of time and, at the moment they are extinguished, the 70 blue light bulbs 6 at the left hand side of the display surface and the red light bulbs 5 at the right hand side of the display surface will be supplied with current. Consequently, at 75 one moment the display surface will be illuminated or displayed in red light rays at the left hand side and blue light rays at the right hand side, and at the next moment, in blue 80 light rays at the left hand side and red light rays at the right hand side. The display matters 4 and 5', in the specific embodiment illustrated constituting the words "Spark" and "Plug" respectively, are, as previously explained, represented in red pigment color and consequently when the left hand side of the 85 display surface is illuminated in red light rays and the right hand side thereof in blue light rays, the word "Spark" will be obliterated and the word "Plug" will appear substantially black on a substantially white background. Similarly, when the left hand side of the display surface is illuminated by blue light rays and the right hand side by red light rays, the word "Spark" will appear 90 substantially black against a white background and the word "Plug" will be obliterated, but the right hand side of the surface will be illuminated in red. Due to the symmetrical arrangement of the red and blue light bulbs, in the manner illustrated in Figure 1, or an equivalent manner, and due to the blending of the complementary spectral colors red and blue, the intermediate portion 95 of the display surface upon which the representation 3 is depicted in neutral pigment color, will appear substantially white and the said representation 3 will, therefore, be visible at all times, the neutral color in which it is represented being substantially unaffected by the spectral light rays by which the 100 display surface is illuminated. Thus, in this application of the principles of the invention, we have the effect of a display surface ranging, in one instance, in color, from red through white to blue and, in the other instance, from 105 blue through white to red. This color change 110 produces a pleasing effect on the observer of the display surface and his attention is attracted and held thereto. It will be evident 115 that in this embodiment of the invention there are present the factors of animation, illumination with color effects, and change in the 120 matters to be displayed, so that, while the spark plug representation 3 is always presented to the vision of the observer, the words 125 "Spark" and "Plug" are caused to be successively presented to his vision, thus impressing on his mind the identity of the article 130 which is being displayed. As previously stated, the example illustrated in Figure 1 of 135

the drawing is a simple one and is intended merely to exemplify one of the possible applications of the principles of the invention and it will be quite evident that a much more complex arrangement of matter to be displayed may be developed under the ingenuity of the designer of the display surface. As distinguished from other applications of the principles of the invention which will be presently explained, it is to be observed that in this instance the representations 4 and 5', being painted in a common pigment color upon a light neutral background, are obliterated under corresponding spectral light rays and displayed to the vision under complementary spectral light rays. It will likewise be understood that, while the representations 4 and 5' have been described and illustrated as red in color, they may be of any other primary color and that the light rays delivered from the sources of illumination will be varied in color to conform with valuations in the colors of the representations 4 and 5'. As a specific example, the words "Spark" and "Plug" might be represented in green pigment color. Instead of representing the words "Spark" and "Plug" in red only, these representations might be painted or otherwise represented in a combination of red, magenta, pink, orange and yellow, all of which colors would disappear under red light illumination and would give varying color graduations under blue or green light illumination.

Figure 2 of the drawing represents a converse application of the principles of the invention. In this figure, the numeral 19 indicates in general a display surface to which there is applied a dark neutral pigment to provide a dark neutral background, indicated by the numeral 20. Matters to be displayed, such, for example, as the words "Spark" and "Plug", indicated by the numerals 21 and 22, respectively, are depicted upon the background 20 in red, in the illustrated embodiment, or in some other primary color or contrasting color. As the background 20 is of a dark neutral color, the representation 23 of a spark plug, which corresponds to the representation 3 in the previously described embodiment of the invention, is in white or some other light neutral color. The red light bulbs 5, and blue light bulbs 6, are arranged in juxtaposition to the display surface to illuminate it in the same manner as the light bulbs in the previously described embodiment of the invention. Current from the source of supply is supplied to the light bulbs and the supply is controlled by a flasher and a system of wiring identical with that shown in Figure 1 of the drawing, therefore requiring no further description. In this application of the principles of the invention, when the left hand side of the display surface is illuminated in red and the right hand side in blue, the word "Spark" or the equivalent representation 21 will appear vividly substantially in white against a black or dark background and the representation 22 or the word "Plug" 70 will be obliterated, and, on the other hand, when the left hand side of the display surface is illuminated in blue and the right hand side in red, the word "Spark" will be obliterated and the word "Plug" will appear 75 vividly and substantially white against a black background. It will be evident that due to the blending of the complementary spectral light rays under which the display surface is illuminated, the intermediate portion of the display surface will be illuminated in substantially white light and, therefore, the representation 23 which is painted in a light neutral color, will stand out vividly 80 against a dark background and will be constantly presented to the view of the observer. It will also be evident that due to the marked contrast between the dark background and the vivid substantially white color in which the representations 21 and 22 are alternately 85 displayed, the sign disclosed in the said Figure 2 will possess exceptional value as a night sign, although, in this case, as in the embodiment of the invention previously described, 90 the display surface possesses all that can be desired as a daylight advertising medium as all of the matters represented upon the surface are visible during daylight hours and, due to the employment of backgrounds of 95 neutral colors, it is possible to employ opaque 100 pigments as distinguished from transparent pigments lacking in distinctiveness. All that has been said with reference to a rearrangement of the matters to be displayed and a complex arrangement and distribution of 105 these matters, with regard to the embodiment shown in Figure 1, applies to that shown in Figure 2. For example, the words "Spark" and "Plug" might be represented in blue or 110 green and the background might be black, brown, dark blue, purple, dark gray, or any other suitable dark neutral color.

In the embodiment of the invention illustrated in Figures 1 and 2, the matters to be displayed are represented, in the first instance, upon a white or light neutral background and, in the latter instance, upon a dark neutral background.

Figure 3 of the drawing represents an embodiment which is of particular value at night and in this figure the display surface is indicated in general by the numeral 58 and, in the specific instance given, has its surface painted with a light neutral pigment 115 to provide a light background 59 of a neutral color. The words "Spark" and "Plug", indicated, respectively, by the numerals 60 and 61, are represented upon the background in some primary or distinctive pigment color, such, for example, as red, and a representa- 120

tion 62 of a spark plug, for example, may be painted in a neutral color upon the said background, the neutral color being, of course, in contrast to the neutral color of the background so that the said representation 62 will be at all times visible against the background. Red light bulbs 63 and blue light bulbs 64 are arranged adjacent the display surface so as to illuminate the same, and the supply of current from the source of supply 65 to the said bulbs, is controlled through the medium of a flasher 66 which is of substantially the same construction as the flasher shown in Figure 1 and previously described, except that in this instance, in addition to the staggered contacts 67 which are carried by the rotating insulating disk 68, two other arcuate contact strips 69 and 70 are arranged upon the face of the disc 68 and are of uniform angular length and longer than the strips 67. In this arrangement, the staggered contact strips 67 are so arranged and wired in the circuit that as they pass beneath the brushes 71 which are in circuit with the sockets for the electric light bulbs 63 and 64, the red light bulbs at one side of the display surface and the blue light bulbs at the other side of the display surface will be simultaneously supplied with current and, vice versa, the blue light bulbs at the first mentioned side of said surface and the red light bulbs at the other side of the surface will be simultaneously supplied with current, and, due to the staggered arrangement of the contact strips, as in the first described embodiment of the invention, the display surface will be successively illuminated in a manner to display the word "Spark" and obliterate the word "Plug" when the left hand and right hand sides of the display surface are respectively illuminated by blue and red light rays and, on the other hand, obliterate the word "Spark" and display the word "Plug" when the left hand and right hand sides are respectively illuminated by red and blue light rays. However, due to the provision of the two relatively long contact strips 69 and 70, and the arrangement of these strips concentrically side by side, as shown in Figure 3, there will be a period of time when all of the lights 63 and 64 will be burning, with the result that the entire display surface will be flooded with substantially white light and, therefore, all of the matter upon said surface will be as vividly and brilliantly brought to the view of the observer as seen under daylight conditions, if not more vividly and brilliantly. It will be evident, therefore, that in this embodiment of the invention, the entire display surface is flooded with white light for a period of time and then its different areas are flooded with complementary light rays which are alternated so as to attract the attention by producing the effect of animation or change in position or character of the matters to be

displayed. It will likewise be evident that by utilizing the principles involved in this form of the invention great latitude is afforded the designer of the display surface and he may, as in the previously described embodiment of the invention, resort to the use of different pigment colors of a contrasting nature or single colors other than red. Likewise, the matters to be displayed may be represented upon a light or a dark background of appropriate neutral colors, or a combination of such backgrounds may be resorted to. Likewise, in this method of display, excellent and pleasing color effects are produced, due to the fact that, while the display surface is being flashed, the red, white and blue spectral colors will illuminate the surface and be reversed, alternately, as regards the position of the red and blue, to produce a pleasing color effect, and to this there is added the brilliant display of the surface when all the light bulbs are burning during the period when the entire surface is displayed. It will be evident at this point that there are three apparent changes or displays instead of two as in the previously described embodiment of the invention.

Having thus described the invention, I claim:

1. Apparatus for producing by illumination change effects in the appearance of represented matters which comprises a display surface having a background of a substantially neutral color and represented matter thereon, said matter being represented in substantially the same pigment color, means for simultaneously illuminating different portions of said surface containing said represented matter by means of different spectral light colors adapted to render a portion of said represented matter clearly visible and to render another portion thereof substantially invisible, thereby producing contrasting change effects on said surface.

2. Means for displaying the effect of change in the appearance of represented matters comprising a display surface bearing upon portions of its area separated matters to be displayed represented in a single distinctive pigment color, and bearing upon another portion of its area matters to be displayed represented in a neutral color, and means for simultaneously displaying the surface in the presence of contrasting spectral light colors of contrasting colored light rays whereby the first-mentioned area portions are illuminated with rays of individual colors.

3. Display apparatus comprising a display surface bearing upon portions of its area matters to be displayed represented in a distinctive pigment color and bearing upon another portion of its area other matters to be displayed represented in a neutral

color and interposed with relation to the first-mentioned matters, and means for simultaneously displaying the surface in the presence of contrasting light rays from sources of mono-chromatic rays whereby to illuminate the first-mentioned area portions with rays of individual colors and illuminate the last-mentioned area portion with the artificial white light rays resulting from blending of the rays from the mono-chromatic sources.

4. Means for displaying the effect of change in the appearance of represented matters by illumination which comprises a display surface having thereon separated matters to be displayed represented in a distinctive pigment color, means for illuminating different portions of said matters simultaneously by different light rays having differing color characteristics, one of said light rays corresponding substantially to the color of said pigment color, means for successively alternating the said illuminating means to produce contrasting effects in the matters displayed, and means for displaying said surface in the presence of said different light rays simultaneously, thereby producing a still different effect.

In testimony whereof I affix my signature.
